UNITED STATES PATENT OFFICE.

PARIS R. FORMAN, OF CHICAGO, ILLINOIS, ASSIGNEE, BY MESNE ASSIGNMENTS, TO
NATIONAL PNEUMATIC COMPANY, A CORPORATION OF WEST VIRGINIA.

PNEUMATIC DOOR-OPERATING MECHANISM.

1,001,942.

Specification of Letters Patent. Patented Aug. 29, 1911.

Application filed September 21, 1907. Serial No. 393,908.

To all whom it may concern:

Be it known that I, PARIS R. FORMAN, a citizen of the United States, residing at Chicago, in the county of Cook, State of Illinois, have made a certain new and useful Invention in Pneumatic Door-Operating Mechanism, of which the following is a specification.

This invention relates to pneumatic door operating mechanism.

The object of the invention is to provide means which are simple and efficient for pneumatically cushioning the opening and closing movements of doors and similar devices and to enable the same to come to rest smoothly and easily and without slam or jar.

A further object of the invention is to provide means in an apparatus of the class described for securing the cushioning effect referred to without the necessity for adjustments after the apparatus is once installed.

Other objects of the invention will appear more fully hereinafter.

The invention consists substantially in the construction, combination, location and relative arrangement of parts all as will be more fully hereinafter set forth, as shown in the accompanying drawing, and finally pointed out in the appended claims.

Referring to the accompanying drawing and to the various views and reference signs appearing thereon, Figure 1 is a view in top plan somewhat diagrammatic, showing a pneumatic controlling and cushioning valve construction embodying the principles of my invention, the valve occupying one of its wide open positions. Fig. 2 is a similar view showing the valve in centered or cut-off position. Fig. 3 is a similar view showing the valve in cushion position. Fig. 4 is a view in elevation showing the application of a controlling valve to a door operating mechanism.

The same part is designated by the same reference sign wherever it occurs throughout the several views.

In carrying out my invention I employ an ordinary pneumatic or compressed air cylinder A, such as is commonly employed in elevator or other door operating mechanism, the supply and exhaust of the operating fluid to and from each end of the cylinder being controlled by a valve arranged within a valve chamber B. In apparatus of this nature, as heretofore constructed, a

slide valve is employed which is given only a very limited movement in either direction,—just sufficient to open and close the ports. In accordance with my present invention, however, I prefer to employ a sliding valve having a circular motion over a plane circular seat, the valve stem being placed at the axial center of the valve and its seat, and the valve extending approximately half way around and held to its seat by the pressure of the operating medium admitted to the valve chamber and superposed thereon. By reference to Figs. 1, 2 and 3, it will be seen that the valve chamber is provided with a main pressure supply port 6, a port 7, leading to one end of the cylinder A, a port 8, leading to the other end of said cylinder and a plurality of exhaust ports, in this instance two, 9 and 10, the former being of large area and the latter of limited or restricted area. The exhaust port 9 of large area should be of sufficient area to permit of the rapid exhaust of the air from one end or the other of the cylinder to which said port may be opened, while the purpose of the exhaust port of limited or restricted area is to permit only a slow exhaust of air from the cylinder. These various ports are controlled by a valve 12, which is rotatively actuated, as above explained by suitably imparting rotative movements to its stem 13. In its under face the valve 13 is provided with a circularly extending recess or groove 14, which, at its extremities is enlarged into the chambers 15, 16. When the valve is moved into position for either of the enlarged chambers 15 or 16 to register with the exhaust ports, as seen, for instance in Fig. 1, all of said ports are uncovered. This occurs at either extreme limit of motion of the valve. When the valve occupies a position intermediate its extreme limits of movement however, as seen in Figs. 2 and 3, only the exhaust port 10, of small area is uncovered while the port 9 of large area is closed. The exhaust port of small area is always uncovered into the recess or passage 14, whatever the position of the valve.

From the foregoing description it will be readily understood that when the valve is in its extreme limit of movement in either direction, one or the other of the ends of the cylinder is freely open to the supply of operating medium, while the opposite end of the cylinder is freely opened to exhaust.

In these circumstances the door begins its movement rapidly, whether it be an opening or closing movement. If, however, the valve is moved from its limit position toward its centered position the exhaust port of large area is closed leaving only the exhaust port of small area open. Consequently, while the pressure medium is still freely admitted to the cylinder at one end, the exhaust from the opposite end of the cylinder can only be effected through the exhaust port of small area, and hence causes the door to move at a decreased speed. This decreased speed of movement of the door continues until the port through which pressure is being supplied to the cylinder is closed which causes an arrest of the movement of the door, and since the slow final movement of the door is against the resistance offered by a limited area of exhaust opening, it is evident that the final arrest of the door movement is without shock or jar or slam due to momentum or otherwise, the door coming to rest easily and smoothly. Thus it will be seen that in starting up the door begins its movement quickly and then by the proper manipulation of the valve the movement of the door is slowed down, and finally the door is brought to rest easily and smoothly.

The manipulation of the valve to accomplish the objects and purposes above noted may be effected in many different ways. In practice, however, I prefer to operate the valve manually to position to inaugurate the movement of the door, and thereafter, to cause the movement of the door or of the door moving means to move the valve automatically to effect the slowing down, or cushioning. Many specifically different constructions and arrangements for accomplishing this result may be employed, the important feature being to close the main exhaust port leaving open only the port of limited area, and providing ample valve movement so that any reasonable amount of variation in such movement will not in the least affect the amount of exhaust opening. Herein lies an important and valuable feature of my invention, since, thereby, it is unnecessary to provide for readjustment of parts after the installation is once made, in order to secure the desired results, whereas, in former constructions where the cushioning effect is obtained by partially closing the ports the slightest variation in the amount of motion given to the valve causes a corresponding variation in the amount of port opening and consequently a variation in the cushioning effect, and as such variation in valve movement may readily occur by wear of the valve moving mechanism constant care and attention and readjustment are necessary in order to secure uniform cushioning results.

In the particular form of mechanism shown for effecting the manual and the auto-

matic operations of the valve, but to which my invention is in no wise to be limited or restricted a rocking lever 20, is pivotally mounted at one end, as at 21, upon the casting 22^a, which carries the toothed gear 28, 70 meshing with rack 27 which is operated by the motor. The other end of this lever 20, is suitably connected by link, rod or other means 23, with a crank arm 24, on the valve stem 13. Also connected to the free end of lever 20, is a rod, link or other suitable connection 25, adapted to be operated by a hand lever or control handle 26. The rack 27, operated by the motor and connected to the cross head 22, operates the toothed gear 28, 80 to which is connected the door operating arm 29. The lever 20 is formed with an enlarged cam-shaped opening therethrough in which operates a pin 40 carried by the rocking door lever operating gear.

The operation is as follows:—In order to inaugurate the movement of the door the hand lever or control handle 26 is manipulated, thereby rocking lever 20, about the point 21 as a fulcrum and, hence, through the connection 23, displacing the valve 12, in the proper direction and extent to open one end of the cylinder to pressure supply and the other end freely to exhaust. Thereupon the motor starts up and the door is 95 moved rapidly. The rocking movement thus imparted to the toothed gear 28 causes the pin 40 to ride upon the cam surface of the opening formed in lever 20, thereby rocking said lever 20 in a direction opposite to that in which the said lever had previously been rocked by the hand lever or control handle, thereby returning the valve a sufficient distance toward its centered or cut-off position to close the large exhaust port. The closing of the large exhaust opening results in slowing down the movement of the door, and enabling the same to be finally brought to rest easily and smoothly.

While I have described my invention as applied to operating and cushioning the movements of doors it is understood that I am not to be limited or restricted in this regard and my invention is equally well adapted for use in many other situations, 105 purposes and uses.

Having now set forth the object and nature of my invention and a construction embodying the principles thereof, what I claim as new and useful and of my own invention 110 and desire to secure by Letters Patent is:

1. In a pneumatic door operating mechanism, a motor, a valve chamber having ports respectively communicating with a source of pressure supply and with opposite sides 125 of the motor, and also having an exhaust opening, a valve for controlling said ports, said valve having a recess to constantly register with a portion of the exhaust opening, said recess being enlarged at its ex- 130

tremities to embrace all of the exhaust opening means for moving the valve to uncover all the exhaust opening to start the motor, door operating connections actuated by the 5 motor, and means also operated by the motor for returning the valve to position to cover a portion of the exhaust.

2. In a pneumatic door operating mechanism, a motor, a valve chamber having ports 10 respectively communicating with a source of pressure supply, and with opposite sides of the motor, and also having an exhaust opening, a valve for controlling said ports, said valve arranged, when at the limit of its 15 movement, in either direction, to open complete communication between a motor port and the exhaust port, and to open the other motor port fully to pressure supply, whereby one side of the motor is opened to pressure 20 supply and the other side to full exhaust, means for moving the valve to the limits of its movement, means operated by the motor for moving the valve in reverse direction, means whereby the reverse movement 25 of the valve reduces the area of exhaust without substantially affecting the pressure supply, as the motor approaches the limit of its action, and door moving devices actuated by said motor.

3. The combination, in a pneumatic door operating mechanism, of a motor, a valve arranged to control the supply of pressure medium to and its exhaust from, said motor, means for shifting the valve into position to open the motor on one side to full supply of pressure, and on the other side to full exhaust, to initiate the operation of the motor, means operated by the motor to reverse shift the valve into position to reduce the exhaust to a constant predetermined area without substantially affecting the supply of pressure, as the motor approaches the limit of its action, and door moving devices actuated by said motor.

4. In a pneumatic door operating mechanism, a motor, a valve chamber having ports respectively communicating with a source of pressure supply and with opposite sides of the motor, and also having an exhaust opening, a valve for controlling said ports, said valve having a recess to embrace within its length a motor port and the full exhaust, means for moving the valve into position for the recess therein to embrace a 55 motor port and full exhaust, to start the

motor, door operating connections actuated by the motor, and means also operated by the motor for returning the valve to position to reduce the area of exhaust without substantially reducing the area of pressure 60 supply.

5. The combination, in a pneumatic door operating mechanism, of a power cylinder, a piston operating therein, a valve chamber having ports respectively communicating with a source of pressure supply and with the cylinder on opposite sides of said piston, said chamber also having a large exhaust port and a small exhaust port, a valve for controlling said cylinder and exhaust ports, means for moving the valve to open the cylinder on one side of the piston to full pressure supply, and on the other side to full exhaust to start the motor, means operated by the motor as the piston 75 approaches the limit of its stroke for moving the valve into position to close the large exhaust port without closing the small one and without substantially affecting the full pressure supply, and door moving devices 80 actuated by said piston.

6. The combination, in a pneumatic door operating mechanism, of a power cylinder, a piston operating therein, a valve chamber having ports respectively communicating 85 with a source of pressure supply and with the cylinder on opposite sides of said piston, said chamber also having a plurality of exhaust ports, a valve for controlling said cylinder and exhaust ports, means for moving the valve to open the cylinder on one side of the piston to full pressure supply, and on the other side to full exhaust through all 90 of the exhaust ports, to start the motor, means operated by the motor, as the piston 95 approaches the limit of its stroke for moving the valve into position to close a portion of the exhaust ports without substantially affecting the full pressure supply, and door moving devices actuated by said piston.

In testimony whereof I have hereunto set my hand in the presence of the subscribing witnesses, on this ninth day of September A. D., 1907.
